US00D357004S

United States Patent [19]**Ando**[11] **Patent Number:** **Des. 357,004**[45] **Date of Patent:** **** Apr. 4, 1995**

[54] **APPARATUS FOR EXTENSION AND
INCREASE OF OPERATION CONTROL
UNIT OF ELECTRONIC COMPUTER**

[75] Inventor: **Takaharu Ando**, Ryugasaki, Japan

[73] Assignee: **Kabushiki Kaisha Toshiba**,
Kanagawa, Japan

[**] Term: **14 Years**

[21] Appl. No.: **12,022**

[22] Filed: **Aug. 20, 1993**

[52] U.S. Cl. **D14/107; D14/109**

[58] Field of Search **D14/100, 102, 107-109;

[57] **CLAIM**

The ornamental design for an apparatus for extension and increase of operation control unit of electronic computer, as shown and described.

DESCRIPTION

FIG. 1 is a top, front and right side perspective view of an apparatus for extension and increase of operation control unit of electronic computer showing my new design;

FIG. 2 is a front elevational view thereof;

FIG. 3 is a right side elevational view thereof the left side being a mirror image;

FIG. 4 is a rear elevational view thereof;

FIG. 5 is a top plan view thereof;

FIG. 6 is a bottom plan view thereof;

FIG. 7 is a sectional view thereof taken along the line 7—7 in FIG. 2 with the internal mechanism being omitted; and,

FIG. 8 is a sectional view thereof taken along the line 8—8 in FIG. 2 with the internal mechanism being omitted.

FIG. 1
FIG. 2FIG.5

FIG.4

FIG.3

FIG. 8

FIG. 7

FIG. 6
